UNITED STATES PATENT OFFICE.

LYMAN S. POWELL, OF CHICAGO, ILLINOIS.

HYDROCARBON GENERATOR AND BURNER.

1,332,003.

Specification of Letters Patent. Patented Feb. 24, 1920.

Application filed February 12, 1918. Serial No. 216,688.

To all whom it may concern:

Be it known that I, LYMAN S. POWELL, a citizen of the United States, and a resident of the city of Chicago, county of Cook, and 5 State of Illinois, have invented Improved Hydrocarbon Generators and Burners, of which the following is a specification.

My invention relates to an improved hydrocarbon generator and burner of the class 10 designed for use primarily in connection with steam-driven vehicles, and has for its object the production of a device of this character, which will be highly efficient in use, permitting of the employment of a low 15 hydrocarbon, such as kerosene for fuel.

A further object is the production of a device as mentioned, in which the flow of fuel will be automatically controlled and in which, by reason of the improved construction of the burner, an intense heat will be produced, when in operation, with a maximum utilization of the fuel before discharge 20 of the same from the device.

Other objects will appear hereinafter.

The invention consists in the combinations 25 and arrangements of parts hereinafter described and claimed.

The invention will be best understood by reference to the accompanying drawings 30 forming a part of this specification, and in which,

Figure 1 is a side elevation of an improved generator and burner embodying the invention,

Fig. 2, an enlarged detail section of the fuel control device embodied in the invention,

Fig. 3, an enlarged detail section of the pressure reducer employed in connection 40 with the pilot light,

Fig. 4, a top plan view of the generator and burner,

Fig. 5, a substantially central vertical longitudinal section of the generator and 45 burner,

Fig. 6, a section taken on substantially line 6-6 of Fig. 5, and

Fig. 7, a section taken on substantially line 7-7 of Fig. 5.

The preferred form of construction as 50 illustrated in the drawings comprises a housing or body 10 upon which, when the device is in use, the boiler 11 used in connection therewith is mounted, as seen in Fig. 1. The interior of housing 10 is divided by a transverse vertical partition 12

into forward and rearward compartments 13 and 14 respectively, a discharge opening 15 leading from the compartment 14. The boiler 11 is of the tubular type, the hot gases 60 generated in the chamber 13 being adapted to pass upwardly through the boiler and afterward downwardly therein into the chamber 14, whence the same are discharged. The precise construction of the boiler, however, forms no part of this application, the same being covered by a separate co-pending application, Serial No. 138,835, filed December 26, 1916.

Arranged in the bottom of chamber 13 is 70 a concavo-convex plate 16 arranged with its concave side down. The plate 16 is perforated except the central portion 17 thereof, which is imperforate, as seen in the several views. Spaced above the plate 16 is a corrugated plate 18 having gas outlet openings which are provided in the crests of the corrugations, as clearly seen in Fig. 6. Provided in the hollows of said corrugations is a filling 19 of asbestos, or other non-heat 75 conducting material which is adapted to keep the lower portion of the plate 18 comparatively cool, when the burner is in operation, and thus serve to prevent back-firing or premature firing. The fuel is supplied to the chamber formed under the plate 16 by mixing tubes 20 which discharge upwardly 80 against the imperforate portion 17 of said plate. By having said plate imperforate at this point, said plate serves as a sort of baffle, 85 inasmuch as the gases impinging thereon will be scattered horizontally and in all directions, with the result that a thorough mingling of the gas and air will be effected 90 at this point.

The tubes 20 open laterally, the same being supplied with fuel from generating pipes 21 which pass over the burner and then connect with branch pipes 22, which in turn communicate with a feed pipe 23 leading 100 to a fuel supply reservoir 24. Interposed in the feed pipe 23 is an automatic pressure control 25 of the conventional diaphragm type, a pressure pipe 25' which leads from the device 25 being adapted to communicate with the boiler in connection with which the generator and burner are employed.

Countersunk in the burner plate 18 is a pilot light 26 comprising two perforated tubes arranged one within the other, as seen 110 in Fig. 6, the inner tube having a flaring mouth 27 into which discharges a nozzle 28,

with which communicates a generating pipe 29. Said generating pipe 29 extends upwardly from the nozzle 28 and thence horizontally over the pilot light burner, being 5 bent upon itself and then carried outwardly and connected with a branch pipe 30 which leads to the feed pipe 23, as clearly seen in Fig. 4. The generating pipe 29 and the branch pipe 30 are connected by a coupling 10 31, as best seen in Fig. 3, in which is arranged a reducer 32 adapted to reduce the pressure of the fuel in the branch pipe 30 before introduction of the fuel into pipe 29.

Arranged for coöperation with the portions 15 of generating pipes 21 and 29 which are arranged over the burner is a primer 33 of the blow-torch type, which is connected through a feed pipe 34 with a reservoir or tank 35 of a fixed combustible mixture such 20 as petroleum. A manually operable valve 36 is interposed in the pipe 34 to control the flow of fuel therethrough. The supply of generating fuel to each of the pipes 21 is automatically controlled through the medium 25 of a differential control device, as best seen in Fig. 2, said device comprising a housing 37 with one end of which the generating pipe 21 communicates, the branch pipe 22 being connected with a laterally projecting nipple provided intermediate the 30 ends of said housing. The opposite end of one of the housings 37 is connected by means of a pipe 38 with the feed pipe 23, the corresponding end of the other housing 37 being 35 connected by a similar pipe 38 with the branch pipe 30, as seen in Fig. 4, the arrangement being such, however, that the last mentioned ends of the housings 37 will be open to the pressure of the supply tank 24 or that to which the pilot light is open. Mounted for reciprocation in each of the 40 housings 37 is a differential piston 39 carrying a needle valve 40 which is adapted to engage a valve seat 41, in order to shut off the flow of fuel from branch pipe 22 to generating pipe 21, as will be readily understood. The arrangement is such, as will be seen, that with the pressure in pipes 22 and 38 the same or equal, the pressure of the fluid in the branch pipe 22 acting on the 45 larger end of the piston 39, will have the effect of holding the latter in a position in which the valve 40 will be open and hence the flow of fuel to the generating pipe 21. 50

55 In the event of the pressure in the branch pipe 22 decreasing, however, the pressure of the fuel in the pipe 38 will operate on the piston, causing the same to be shifted to a position in which valve 40 will be closed, and thus the supply of fuel to the generating pipe 21 shut off.

In the operation of the device it will be seen that the liquid fuel contained in the reservoir 24, will pass therefrom through the pipe 23 and flow into pipes 22, 30 and

38. The fuel after passing through the branch pipes 22 will pass through the generating pipes 21, where the same will be heated, providing the burner below is in operation. The heating of generating 70 pipes 21 of course effects generation of gas from the liquid fuel, this gas being discharged into the pipes or tubes 20 where the same is mingled with air. The thorough mingling of the air and gas is further 75 accomplished after discharge from said pipes or tubes, by striking the plate 16 and subsequently passing through the perforations therein and in the burner plate 18. Likewise, the fuel passing through the 80 branch pipe 30 flows into the generating pipe 29 where the same is subjected to the heat from below, causing generation of gas, this gas being discharged into the pilot light burner 26, where the same is mixed with 85 air before being discharged for burning. The branch pipe 30 is in direct communication with the feed pipe 23, so that the pilot light will be continuously burning during 90 operation of the vehicle.

When the pressure in the boiler reaches a predetermined point, the same will operate on the control device 25 causing restriction of the flow of fuel to the branch pipes 22. This restriction causes reduction of the pressure in said pipes which in turn results in the instantaneous shifting of the differential pistons 39, causing closing of the valves 40, thereby shutting off the flow of fuel to the generating pipes 21, with the result of 100 dampening or diminishing the heat under the boiler. As the pressure in the boiler reduces, the pressure control 25 will open and again permit of unrestricted flow of fuel to the branch pipes 22, when the pistons 39 will be moved to open the valves 40. Thus, it will be seen, that the flow of fuel to the main burner of the device, will be 105 automatically controlled with the result of maintaining a uniform pressure in the boiler. 110

The primer will be used only in the initial starting of the device, in order to initially heat the generating pipes 21 and 29, to obtain the initial gas generation. After the device has thus been started, the same will 115 supply its own heat for gas generation, after which time the device will be automatic in its operation, as will be readily understood. The quick acting fuel shut off, controlling the flow of fuel to the main burner, is of 120 special advantage in that it prevents any waste of fuel, such as otherwise results where the action of the control device is not instantaneous, as in applicant's arrangement. Also the provision of the reducing 125 nozzle 32 at the entrance of the fuel supply pipe to the pilot light, results in a comparatively small flame being maintained at this point, and eliminates any noise such as would be incident to the supplying of 130

fuel under full pressure to the comparatively small pilot light burner.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters

15 Patent is:

1. A generator and burner of the class described comprising a burner element; a pilot light arranged for coöperation with said burner element; a source of fuel supply 20 communicating with said burner element and said pilot light; means for automatically stopping the flow of fuel to said burner element when the pressure of the fuel to said burner element is reduced, said means 25 comprising a shiftably mounted differential piston; and a valve operable by said piston for controlling the flow of fuel to said burner element, the opposite ends of 30 said piston being exposed to the pressure of the fuel supplied respectively to said burner element and pilot light, substantially as described.

2. A generator and burner of the class described comprising a burner element; a source of fuel supply communicating with said burner element; means for automatically stopping the flow of fuel to said burner element when the pressure of the fuel supplied to said burner element is reduced, said 35 means comprising a shiftably mounted differential piston; and a valve operable by said piston for controlling the flow of fuel to said burner element, the opposite ends of 40 said piston being exposed to the pressure of the fuel at said source and at said burner element respectively, substantially as described.

3. The combination with a boiler, of a generator and burner comprising a burner

element; a source of fuel supply communicating with said burner element; means for automatically reducing the pressure of the fuel to said burner element when the pressure in said boiler rises above a predetermined point; means for automatically stopping flow of fuel to said burner element when the pressure of fuel to said burner element is reduced, said means comprising a shiftably mounted differential piston; and a valve operable by said piston for controlling the flow of fuel to said burner element, one end of said piston being exposed to the pressure of the fuel supplied to said burner element, substantially as described.

4. A generator and burner of the class described comprising a burner element; a pilot light arranged for coöperation with said burner element; a source of fuel supply communicating with said burner element and said pilot light; means for automatically stopping the flow of fuel to said burner element when the pressure of the fuel to said burner element becomes less than the pressure of the fuel to said pilot light, substantially as described.

5. The combination with a boiler, of a generator and burner comprising a burner element; a pilot light arranged for coöperation with said burner element; a source of fuel supply communicating with said burner element and said pilot light; means for automatically reducing the pressure of the fuel to said burner element, without disturbing the pressure of the fuel to said pilot light, when the pressure in said boiler rises above a predetermined point; and means for automatically stopping the flow of fuel to said burner element when the pressure of the fuel to said burner element is reduced, substantially as described.

In testimony whereof I have signed my name to this specification in the presence of two subscribing witnesses.
